UNITED STATES PATENT OFFICE.

LEE E. ALLEN AND JOHN K. FURST, OF NEW CASTLE, PENNSYLVANIA, ASSIGNEES TO PENNSYLVANIA ENGINEERING WORKS, OF NEW CASTLE, PENNSYLVANIA, A CORPORATION OF PENNSYLVANIA.

HOT-METAL MIXER.

Application filed July 8, 1926. Serial No. 120,657.

This invention relates to metallurgical apparatus, and more particularly to receptacles for holding and mixing molten metals and commonly known in the art as hot metal mixers.

Hot metal mixers, as heretofore used, have generally been of two very distinct types. The first type, most commonly in use, comprises a refractory lined receptacle having a substantially semi-circular bottom with a flattened arched top, and with spouts at opposite sides thereof. These receptacles are generally mounted on trunnions or rockers, and have a mechanism for effecting a tilting motion thereof.

In the second type which has more recently been adopted, and which is used especially in mixers of very large capacity, the mixer is substantially cylindrical with a spout in one end at one side thereof for receiving the hot metal and a second spout on the opposite side at the other end from which hot metal may be poured. The mixer of this type is also mounted on trunnions or rollers and has a mechanism for tilting it.

The former type of mixer has certain disadvantages, especially where it is of large capacity due to the fact that quite an elaborate structural metal frame is necessary for bracing the shell of the receptacle, it being necessary to provide a series of I-beams under the bottom thereof to secure proper strength for the bottom of the receptacle. Another difficulty with a mixer of this type arises from the fact that it must have rather sharp corners at certain points therein, particularly adjacent the spouts, and the refractory linings at these corners are rapidly eroded by the hot metal. The corners serve, furthermore, to form dead pockets where the metal and slag may become more or less stagnant and prevent it from mixing as much as desired with the other metal in the receptacle.

The type of mixer having a cylindrical receptacle can be more readily braced than the first type mentioned, the bracing consisting primarily of a series of hoops or annular beams surrounding the shell of the receptacle. The cylindrical mixer, however, is not in all cases as desirable a form as the first type in cases where the physical and chemical properties of the iron cause it to be sluggish and viscous, as in these cases the first type, on account of its direct course,

make it easier for the passage of the metal through the mixer with an accumulation of less slag skulls.

According to the present invention it is proposed to modify the shape of the receptacle of the first type in such way as to simplify the bracing thereof and eliminate much of the structural metal required for bracing mixers of this type, adapting the mixer to a system of bracing somewhat similar to that employed in connection with the cylindrical type mixers.

The invention has for a further object to provide a mixer wherein the inlet and outlet spouts may be oppositely located and wherein the receptacle may have a large capacity relative to its overall dimensions and wherein sharp corners are eliminated so that the lining is less subject to erosion and the formation of dead pockets avoided.

A further object of the invention is to provide an improved shape for the receptacle wherein the lining is arched in all directions, thereby securing added strength and life to the lining and permitting of more efficient bracing of the shell of the receptacle.

The invention has for a further object to provide an improved rocker construction for the receptacle and to provide an improvement in the operating mechanism for rocking the receptacle wherein wear of the parts may be readily detected and lubrication thereof assured.

The invention may be understood by reference to the accompanying drawings which illustrate one embodiment of our invention, and in which:

Figure 1 is a top plan of the mixer and operating means therefor;

Figure 2 is a side elevation of the apparatus disclosed in Figure 1;

Figure 3 is a broken section showing an end elevation of a part of the mixer and showing a vertical longitudinal section through a part of the mixer;

Figure 4 is an enlarged detail view of the lubricating mechanism for the operating screw;

Figure 5 is a detail inverted perspective view of one end of operating nut which operates with the operating screw.

Referring more particularly to the drawings, 5 designates the receiving chamber of the hot metal mixer and 6 and 7 are receiv-

ing and discharge spouts respectively. The main body of the receptacle is bowed outwardly with respect to the longitudinal axis thereof, this axis being represented by the 5 broken line A—A in Figure 1. The lower portion of this receptacle is transversely circular, being of decreasing diameter toward the ends by reason of the bowed shape of the receptacle, while the roof of the receptacle 10 is somewhat flattened, as indicated by the part 8. In other words, the receptacle is substantially barrel-shaped as clearly shown in Figure 1, but has its top side slightly flattened as most clearly indicated in Figure 2. 15 The two end walls 9 of the receptacle are outwardly arched, thereby providing a spherical interior wall at the inner ends of the chamber 5.

Substantially the entire structure has a 20 shell 10 made up of metal plates, and this shell supports the refractory lining 11.

The shell is braced by a plurality of structural bands or hoops 12, preferably two one of which is located at each side of the 25 spouts 6 and 7. These annular bands 12 are connected at several points around the receptacle by longitudinally extending tension rods 13 about which are spreaders or spacing sleeves 14. In addition to this, metal bands 30 15 may be suitably arranged longitudinally of the central portion of the receptacle and similar bands arranged radially, and designated 16, may be provided on the spherical ends.

35 Due to the particular barrel-shape of the receptacle, together with the spherical ends thereof, sharp corners are avoided so that the lining is not washed away at particular points by the erosive action of the molten metal. The lining is arched in all directions 40 so that its has a maximum strength and life, and by reason of the barrel-shape of the steel frame the supporting sides of the receptacle are thrown into tension, giving increased strength to the frame work and requiring that it be less heavily constructed 45 than where the supporting sides are in compression. In addition, a large capacity is obtained relative to the overall dimensions 50 of the structure.

The structural bands 12 not only provide the main supporting frame for the mixer, but provide rockers for engagement with the rollers on which the receptacle is supported. 55 These rollers are clearly shown in Figure 2 and are of the double equalizing type. The mounting for the mixer includes the base 17 having opposed holders 18 pivotally supported thereon at 19. Each of the 60 holders 18 in turn carries two smaller holders 20 thereon pivotally supported in the holders 18 at 21. Each of the holders or equalizers 20 carries a pair of rollers 22 which are flanged. A support of this kind is provided 65 at each side of the receptacle, and the respec-

tive bands 12 are set on the rollers thereof. The mixer may be tilted on the rockers in the usual manner. In accordance with the usual practice we prefer to use two operating mechanisms designated generally as 70 23 and more or less diagrammatically illustrated in Figures 1 and 2. Each operating means 23 includes a screw shaft 24 operatively connected with a motor 25 and movable along the threaded portion of the shaft is 75 a nut 26. Connected with the trunnions 27 on the nut 26 are links 28 whose other ends pivotally connect to the underside of the receptacle at 29. Upon rotation of the screws 24 the nuts 26 are reciprocated to effect a tilting or restoring movement to the receptacle. Each of the nuts 26 is preferably of the construction shown in Figure 5, having a main portion 26^a which is of the usual form and projecting from at least one end thereof is 80 an extension 26^b that engages only the upper portion of the threaded shaft 24. The advantage of this particular construction resides in the fact that when wear develops in the threads, it can be readily observed by merely looking at or feeling the fit of the threads between the shaft 24 and the threads on the extension 26^b.

We also preferably employ means for positively lubricating the nuts 26. To this end, 85 each nut operates in a trough 30 which is preferably covered and which has a longitudinal slot 31 therealong. The lubricating system itself is best shown in Figure 4 and includes a nozzle 32 secured to the nut and 90 opening into a passage that communicates with the interior threads of the nut.

This nozzle has a T connection 33 at its upper end. Leading in opposite directions from the T 33 are pipes 34 in which are 95 check valves 35. Each of the pipes 34 passes through a packing 34^a at the end of a cylinder 36 and has a piston 37 at its end, this piston being open so that fluid may pass from the cylinder into the pipe. Extending down from each of the cylinders 36 is an intake pipe 38 having a strainer 39 at its lower end, this strainer having a check valve associated therewith.

The arrangement of the check valves in 115 the system is such that when the nut is traveling along the screw in one direction, the check valve 35 on the side in the direction of travel of the nut will be open and the check valve in the strainer at 39 on the side 120 toward which the nut is travelling will be closed. The other check valve 35 will be closed and the other check valve at 39, away from which the nut is moving will be open. With this arrangement oil or lubricant will 125 be sucked up the pipe 38 into the cylinder 36 away from which the nut is moving while oil which has previously entered the cylinder 36 toward which the nut is moving will be confined against escape and will be forced 130

through the pipe 34, the check valve 35 and down the nozzle 32 into the threads of the nut. When the nut travels in the reverse direction the action of the two pumps will be 5 reversed. The terminals 39 on the pipes 38 are located at opposite ends of the troughs 30.

With this mechanism positive lubrication of the nuts and of the threaded shafts is assured, and lubrication is effected 10 only when it is needed and without necessitating the provision of lubricating means operated entirely independently of the mixer rocking mechanism.

The advantages of our invention arise, as 15 hereinbefore stated, from the improvement in the shape of the mixer by means of which longer life of the lining is assured and by means of which the construction of the structural frame therefor can be materially 20 lightened, and in the use of double equalized supporting rollers for the receptacle. Further advantages arise from the use of a positive lubricating means of novel construction for the mixer tilting mechanism, 25 and in the provision of a nut of such construction that wear in the threads can be readily detected.

While we have illustrated and described a preferred embodiment of our invention, it 30 will be understood that the invention is not confined to the particular arrangement and embodiment disclosed, but that it may be otherwise embodied within the spirit of our invention and under the scope of the appended claims.

We claim:

1. A hot metal mixer comprising a body which is outwardly bowed between its ends relative to its longitudinal axis, ends on the 40 body which are rounded outwardly both transversely and vertically, said ends being closed below the longitudinal axis of the body, the top of said body being transversely curved to a less extent than the remaining portion of the body, spouts located 45 on opposite sides of the body intermediate its ends, and means for tiltably supporting the body.

2. A hot metal mixer comprising a substantially barrel-shaped body having annular supporting rings adjacent the end portions thereof, tension rods connecting the supporting rings, and means for tiltably supporting the body.

3. A hot metal mixer comprising a substantially barrel-shaped body, supporting rings on the body adjacent opposite ends thereof, tension rods connecting the supporting rings, and spreaders around the tension rods between the rings.

4. A hot metal mixer comprising a substantially barrel-shaped body having outwardly rounded ends, spouts on the body intermediate the ends thereof, a supporting 65 ring encircling the body adjacent each end

thereof, and tension rods connecting the supporting rings.

5. A hot metal mixer comprising a substantially barrel-shaped body having outwardly rounded ends, spouts on the body intermediate the ends thereof, a supporting ring encircling the body adjacent each end thereof, a substantially barrel-shaped structural metal frame surrounding the body and connected with the rings, and means secured 70 to each ring connecting the rings and holding them in spaced relation.

6. The combination with a hot metal mixer having supporting rockers thereon, of a supporting means including a base, a 80 pair of tilttable holders on the base under each rocker, a pair of smaller holders pivotally carried on each of said first holders, and rollers on the smaller holders engaging the rockers of the mixer. 85

7. The combination with a hot metal mixer of reciprocating means therefor including a link, a nut to which the link is connected, a threaded shaft with which the nut cooperates, and means for rotating the 90 shaft, said nut having an extension on one end thereof, said extension being threaded and engaging a portion of the threaded shaft only whereby any looseness between the threads on the shaft and the threads on 95 the nut may be seen.

8. The combination with a hot metal mixer, of means for effecting a tilting motion thereof including a threaded rotatable shaft, a nut cooperating with said shaft and 100 lubricating means for the nut including a pump operatively connected with the nut.

9. The combination with a hot metal mixer, of means for effecting a tilting motion thereof including a threaded rotatable 105 shaft, a nut cooperating with said shaft and lubricating means for the nut, said means including a pump having a cylinder and a piston, said piston being operatively connected with the nut whereby oil is pumped to the 110 nut upon reciprocation of the nut along the threaded shaft.

10. The combination with a hot metal mixer, of means for effecting a tilting motion thereof including a threaded rotatable 115 shaft, a nut cooperating with said shaft and lubricating means for the nut including a pump, said means including a pair of oppositely located cylinders having valved intake connections, each of said cylinders having a piston slidably therein, a pipe rigidly connecting each piston with the nut, said pipes having check valves therein, whereby oil is pumped alternately to the nut from the respective cylinders upon reciprocation 120 of the nut along the screw.

In testimony whereof we have hereunto set our hands.

LEE E. ALLEN.
JOHN K. FURST.
